DESIGN FOR A BABY'S BOOTEE DRIER

Mary G. Fitts, Atlanta, Ga.

Application March 26, 1945, Serial No. 118,711

Term of patent 7 years

(Cl. D33--1)

To all whom it may concern:

Be it known that I, Mary G. Fitts, a citizen of the United States, residing at Atlanta, in the county of Fulton and State of Georgia, have invented a new, original, and ornamental Design for a Baby's Bootee Drier, of which the following is a specification, reference being had to the accompanying drawing, forming part thereof.

Fig. 1 is a front view of a baby's bootee drier showing my new design.

Fig. 2 is a top plan view thereof,

Fig. 3 is an end view, and

Fig. 4 is a transverse vertical section taken on the line 4—4 of Fig. 1 with the bootee supporting element in side elevation.

I claim:

The ornamental design for a baby's bootee drier, substantially as shown.

MARY G. FITTS.
